UNITED STATES PATENT OFFICE.

JAMES D. BERGEN, OF HARTFORD, ASSIGNOR TO THE J. D. BERGEN COMPANY, OF MERIDEN, CONNECTICUT.

DESIGN FOR A GLASS VESSEL.

SPECIFICATION forming part of Design No. 23,316, dated May 29, 1894.

Application filed January 15, 1894. Serial No. 496,985. Term of patent 7 years.

To all whom it may concern:

Be it known that I, JAMES D. BERGEN, of Hartford, in the county of Hartford and State of Connecticut, have invented a new Design 5 for the Ornamentation of Glassware; and I do hereby declare the following, when taken in connection with accompanying drawings and the letters of reference marked thereon, to be a full, clear, and exact description of 10 the same, and which said drawings constitute part of this specification, and represent, in—

Figure 1, a plan view of a bowl containing my design; Fig. 2, a view thereof in vertical central section.

15 This invention relates to a design for the ornamentation of glass vessels, and the design consists in the configuration and ornamentation as shown in the accompanying illustration, its predominant feature being 20 two parallel, horizontal grooves concentric with the center of the vessel, radial grooves which intersect the said horizontal grooves at a right angle, and tangential grooves which intersect the said horizontal grooves, the radial 25 grooves, and each other.

The edge of the design consists of a series 30 of fan-like figures A, having curved indented edges, and placed point to point. The surface below the fans is divided into small raised triangular figures B, varying in size 35 and shape, and cross-hatched by shallow cuts or grooves. The said triangular figures are formed by deep radial grooves C, extending inward from the meeting points of the fans, by deep radial grooves C' extending inward 40 from the apices, so to speak, of the fans, by deep parallel horizontal grooves D D', the former intersecting the radial grooves C and the apices of the fans, and the latter intersecting both the radial grooves C, and the ra-

dial grooves C', and by deep tangential or inclined grooves E and E' extending in opposite directions, intersecting each other at a right angle, and intersecting the other grooves at angles other than a right angle. The 45 grooves E extend outward between the fans, which may be said to interrupt the grooves E' which extend outward and stop midway between the sides of the fans. The surface of the glass below the edge formed by the 50 fan-like figures is therefore broken by deeply cut grooves intersecting each other at different angles, and producing a striking and ornamental effect. The effect of the grooves in one view of them is to form a series of corresponding star-like figures having arms of different lengths, the arms being formed by the intersections of the grooves.

The predominant feature of my present design lies in the two horizontal grooves concentric with the center of the vessel, in the radial grooves which intersect the said horizontal grooves at a right angle, and in the tangential grooves which intersect the horizontal grooves, the radial grooves, and each 60 other, all of the said grooves combining to divide the central portion of the vessel into a large number of triangular figures varying in size and form.

I claim—

70 The design for the ornamentation of glass vessels as herein shown and described.

In testimony whereof I have signed this specification in the presence of two subscribing witnesses.

JAMES D. BERGEN.
